United States Patent Office

Des. 195,579
Patented July 2, 1963

195,579

EDUCATIONAL SPINNING TOY

Max J. Ruderian, 545 Hanley Ave., Los Angeles, Calif.

Filed Jan. 31, 1963, Ser. No. 73,396

Term of patent 14 years

(Cl. D34—5)

FIG. 1.

FIG. 2.

FIG. 3.

FIGURE 1 is a top plan view of an educational spinning toy showing my new design;

FIGURE 2 is an edge elevational view thereof; and,
FIGURE 3 is a bottom plan view thereof.

I claim:

The ornamental design for an educational spinning toy, substantially as shown.
